JACK AND JIGGLE JACK

Marcel Garancher, Chicago, Ill., assignor to
Stewart-Warner Corporation, Chicago, Ill., a
corporation of Virginia

Application April 8, 1943, Serial No. 482,242

9 Claims. (Cl. 121—164)

1

This invention relates to an air operated jack and jiggle jack for use with vehicles.

One object of this invention is to provide a jack which will collapse to small dimensions and which can be used wherever air pressure is available for lifting the vehicle, or a part thereof, and holding it in its lifted position, or for lifting and lowering the chassis of the vehicle repeatedly and automatically for the purpose of freeing up the spring shackle bearings and for assisting in working grease into such bearings.

Another object of my invention is to provide a jack which can be readily adjusted by hand to a position to contact with the part of the vehicle to be lifted and thereafter be operated by air pressure to raise and lower the vehicle part with which the jack has been connected.

Another object of my invention is to provide means for causing the jack to jiggle with a stroke less than that of which the jack is capable when used only for hoisting.

Another object of my invention is to provide a jack in which the movable parts are suitably protected against dirt which frequently falls upon the jack from the vehicle.

Still other objects and features of my invention will appear from the following specification and drawings, in which like parts are designated by like characters throughout the several views.

My invention is illustrated in the accompanying drawings, in which

Fig. 1 is a plan view of the top of the jack;

Fig. 2 is a vertical sectional view showing the jack in its fully collapsed condition;

Fig. 3 is a fragmentary section taken on the line 3—3 of Fig. 1;

Fig. 4 is a vertical sectional view showing the two jack extension members adjusted into their raised positions;

Fig. 5 is a horizontal sectional view taken on the line 5—5 of Fig. 2;

Fig. 6 is a horizontal section taken on the line 6—6 of Fig. 2;

Fig. 7 is a horizontal section taken on the line 7—7 of Fig. 2;

Fig. 8 is a horizontal section taken on the line 8—8 of Fig. 2;

Fig. 9 is a horizontal section taken on the line 9—9 of Fig. 2;

Fig. 10 is an enlarged fragmentary vertical section taken through the center of the valve mechanism for the jack;

Fig. 11 is a horizontal section taken on the line 11—11 of Fig. 2;

2

Fig. 12 is a vertical section taken on the line 12—12 of Figs. 10 and 11;

Fig. 13 is a vertical section taken on the line 13—13 of Fig. 10;

Fig. 14 is a horizontal section taken on the line 14—14 of Fig. 10;

Fig. 15 is a vertical section taken on the line 15—15 of Fig. 10;

Fig. 16 is a horizontal section taken on the line 16—16 of Fig. 10; and

Fig. 17 is a fragmentary vertical section of the jack showing the slide valve in the position in which the passages communicate with one another for the exhaust of the air from the cylinder in jiggle jack operation.

Referring more particularly to Fig. 2, in which the jack is illustrated in its completely collapsed condition, a base member 20 supports a cylindrical housing 21 at the top of which a guide ring 22 is mounted and held in place partly within and partly upon the upper end of the cylindrical housing 21 by means of a pair of arcuate clamps 24 and 25 drawn together about the periphery of the cylinder 21 and guide ring 22 by means of bolts 26 and 27. The cylindrical housing 21 is provided with a groove 29 near its upper end, into which correspondingly shaped portions of the clamps 24 and 25 project, and the guide ring 22 is provided with a shoulder 30, above which portions of the clamp members 24 and 25 abut, thus holding the guide ring 22 and the cylindrical housing 21 firmly together against a very high pressure, which may be applied to the under side of the ring when the jack is in its uppermost position under the influence of high air pressure. A partition 31 extends across the cylinder 21 and is suitably welded in place to form the lower cylinder head.

The piston for raising the jack comprises a circular disc 33, an abutting cup washer 34, a spring cup washer expander 35 and a cup shaped metallic protector and stop member 36, all held together by means of a hollow nut 37 threaded into the central opening through the plate 33 and having a shoulder 38 which clamps the metallic cup member 36, the spring expander 35 and the cup washer 34 firmly together in the order named on the bottom of the circular piston disc 33.

A cylindrical piston rod 40 of a diameter to provide a working fit within the guide ring 22 is secured by means of a plurality of screws 41 to the upper face of the circular piston disc 33, the diameter of the piston rod 40 being somewhat less than the internal diameter of the cylindri-

cal housing 21. Suitably welded, or otherwise sealingly mounted, within a hollow portion of the nut 37 is a vertically extending tubular spring housing 43 closed at its top by means of a cap 44 threaded over the outside of the tubular spring housing 43. The interior of the tubular spring housing 43 is in communication with the space below the group of piston members 33, 34, 35 and 36.

A ring 46 is secured within the upper end of the cylindrical piston rod 40 by a press fit against a shoulder 47 formed on the inner wall of the cylindrical piston rod 40. The opening through ring 46 has a greater diameter in one direction than it has in the direction at 90 degrees thereto, as shown in Fig. 9.

Extending through the opening in the ring 46 is a lifting member 48 having wings 49 and 50 registering with the elongated portions of the opening through the ring 46. The lifting member 48 is in the form of a sleeve, the foot 51 of which rests upon the upper surface of the piston plate 33. The foot of the sleeve 48 is enlarged to the diameter of the inside of the cylindrical piston rod 40. The sleeve 48 is also provided with a second set of wings 52 and 53, shown in cross section in Fig. 8, and located substantially midway between the upper pair of wings 49 and 50 and the foot 51 at the bottom of the sleeve 48.

The upper portion of the lifting sleeve 48 is internally threaded at 55 to receive a screw 56 carrying at its top a revolvable shoe 58 having a downwardly projecting stem 59 rotatably mounted within the cylindrical interior of the screw 56. The shoe 58 is provided with a plurality, preferably four, of small projections 60 to prevent the shoe from slipping off of a portion of a vehicle against which it is pressing for lifting or jiggling purposes. The stem 59 is prevented from making a complete revolution within the screw 56 by means of a set screw 61 which extends into a groove 62 (Fig. 5), which is cut only part way around the stem 59. A ball 63 is pressed by a spring 67 against the inner surface of the cylindrical screw 56 to prevent a too ready rotational movement of the stem 59 within the screw 56.

A metallic disc 69 (Fig. 6) is provided with a tongue 70 extending into a keyway 71 cut lengthwise of the lifting sleeve 48. The periphery of the metallic disc 69 rests loosely upon a shoulder 72, formed at the top of the inner wall of the cylindrical piston rod 40, the metallic disc 69 being rotatable with the lifting sleeve 48 and rotatable within the cylindrical piston rod 40.

An operator desiring to place the jack under a part to be lifted rotates the shoe 58 by means of the projections 60, thus raising the screw 56 within the lifting sleeve 48 until the shoe 58 contacts the part of the vehicle to be raised, or else until the screw 56 comes to the end of its movement. If at this time the shoe 58 is still a considerable distance below the part of the vehicle on which the raising force is to be applied, the shoe 58 is lifted by hand until either the upper pair of wings 49 and 50 is raised above the upper surface of the ring 46, or if this is not high enough, then until the lower pair of wings 52 and 53 is raised above the upper surface of the ring 46.

At one of the two before mentioned raised positions of the lifting sleeve 48 the operator rotates the sleeve 48 through 90 degrees to permit one of the sets of wings, either 49 and 50 or 52 and 53, to rest in depressions 54 of the same shape

as the wings formed in the opposite solid portions of the ring 46. The piston is now raised by the application of compressed air between the cup washer 34 and the cylinder head 31, the lifting sleeve 48 being raised either by reason of the fact that its foot 51 rests upon the upper surface of the piston disc 33, or by reason of the fact that one or the other of its pairs of wings 49 and 50, or 52 and 53, rests upon the solid portions of the ring 46, which rises with the piston rod 40.

In all of the various positions of elevation of the parts of the jack the screw 56 is held in axial alignment with the cylinder 21 by the threads in the lifting sleeve 48. The lifting sleeve is held in axial alignment with the cylinder 21 by its circumferential foot 51, and by the close fit of its upper portion within the opening through the ring 46. The piston rod is held in axial alignment with the cylinder 21 by means of the cupped plate 33, which contacts the inner wall of the cylinder 21 at a low point, and the guide ring 22, which contacts the piston rod 40 at a point always somewhat remote from the point of contact of the metallic cup 33 within the cylinder wall.

Provision in the form of one or more grease nipples 73 communicating with a circumferential grease passage 74 on the inner surface of the guide ring 22 facilitates lubrication of the working surfaces of the guide ring 22 and the cylindrical piston rod 40. The lifting stroke of the jack is the distance between the upper surface of the circular plate 33 and the lower surface of the guide ring 22.

Because my pneumatic jack is arranged for automatic operation to raise and lower the vehicle periodically, or for manual operation to raise and lower the vehicle at will, certain valve mechanisms are provided for admitting and relieving the air in accordance with the desired operation.

The automatic valve mechanism as shown in Figs. 10, 11, 12 and 17 comprises a mechanism to be hereinafter fully described for moving a slide valve member 77 from its lower position, shown in Fig. 10, to its upper position, shown in Fig. 17. This slide valve member 77 includes a rectangular block with a depression 78 milled into one side for completing or cutting off communication between the passageways 79 and 80 drilled through the polished faced, generally cylindrical plug 81. The opposite side of the slide valve member 77 is provided with a milled slot 82 cut with the axis of the miller in a plane at right angles to the plane of the axis of the miller with which the depression 78 is cut. The purpose of the depression 82 is to form an abutment against a circumferential ridge 83 formed between two circumferential valleys 85 and 86 in the reciprocable operating sleeve 88 (Figs. 11 and 12) to prevent the valve block 77 from moving laterally across operating sleeve 88.

Balls 89 and 90 pressed into the valleys 85 or 86 by springs 92 and 93 serve to hold the reciprocable operating sleeve 88, and consequently the valve block 77, in either their upper or lower positions. The interior of the reciprocable sleeve 88 is provided at its center with an integral inwardly projecting ring 94 forming seats for the springs 95 and 96. The ends of the springs 95 and 96, remote from the ring 94, abut shoulders 97 and 98, respectively, carried by an operating rod 99.

The springs 95 and 96 are of such length that they are continuously slightly compressed between the shoulders 97 and 98 and are of such

strength that when the operating rod 99 is moved downwardly, as will be hereinafter described, the reciprocable sleeve 88 will move with a snap movement from its upper position, in which the balls 89 and 90 rest in the valley 86, to its lower position in which the balls 89 and 90 rest in the valley 85. When the operating rod 99 is moved upwardly, as will be hereinafter described, the compression of the spring 96 overcomes the pressure of the spring 95 and permits the reciprocable sleeve 88 to move with a snap action to its upper position.

The movement of the operating rod 99 from one position to the other will be most readily understood by reference to Figs. 2 and 17. The operating rod 99 extends upwardly through a packing gland 100 and into the spring housing 43 which is movable with the piston members of the jack. The upper end of the operating rod 99 is reduced in size providing a shoulder 102, upon which a movable abutment 103 and a spring 104 normally rest. The upper end of the spring 104 abuts the cap 44 at the upper end of the spring housing. The extreme upper end of the rod 99 carries a nut 105 of a size which will not pass through the opening in the movable spring abutment 103.

As the jack piston rises the spring 104 gradually elongates until the abutment 103 rests upon the circumferential stop 107 formed within the clamping nut 37. Throughout that portion of the movement of the jack piston upwardly in advance of the contact of the movable spring abutment 103 with the stop 107, the spring 104, by its downward pressure on the operating rod 99, holds the reciprocable sleeve 88 in its lower position.

When the jack piston has risen substantially to its uppermost position, the nut 105 on the upper end of the operating rod 99 encounters the upper surface of the movable spring abutment 103 pulling upwardly on the rod 99 and compressing the spring 96 until its pressure so far overbalances spring 95 that the reciprocable sleeve 88 snaps from its lower position to its upper position. Conversely, as the jack piston moves to its lower position, the shoulder 102 engages the under side of the spring pressed movable abutment 103 producing a downward movement of the operating rod 99, which compresses the spring 95 and elongates the spring 96 causing the reciprocable sleeve 88 to snap to its lower position. The automatic reciprocation of the piston takes place, therefore, as hereinafter described, between the top of the stroke of the piston and that partially contracted position in which the shoulder 102 contacts the movable abutment 103. The pressure of spring 104 is sufficient to trip the valve rod 99 but is insufficient to prevent the jack from fully retracting under its own weight when the air pressure is manually cut off and the relief valve is manually opened.

The reason for preventing the jack from moving to its fully contracted position during jiggling is that the jack must be placed by hand under the part to be jiggled and, therefore, will not always be tight between the ground and the part to be jiggled before the air is applied. If the jack returned to normal at the lower end of each jiggle stroke, it would be likely to work itself out from under the part being jiggled.

The passageways through which the compressed air is admitted to and relieved from the space beneath the cup washer 34 of the jack piston are most readily traced in Figs. 10 to 16, in-

clusive. Air under pressure is fed to the jack through conduit 110. A conical valve 111 operating on a seat 112 by means of a hand wheel 113 admits high pressure air into the pipe 115 communicating with the valve chamber 116.

A double seated valve 118 in the chamber 129, provided with sealing rings 119 and 120, is moved between its seats 121 and 122 by means of a shank 123 threaded in a packing gland nut 124 and provided at its outer end with a hand wheel 125. The function of the valve 118 is to change the jack from its mere hoisting function to its jiggling function. The valve 118 is shown in Figs. 10 and 11 in the position for the hoisting function.

When the valve 118 is in its hoisting position, compressed air from the valve chamber 116 passes through drilled conduit 121 and lateral conduits 128 to the chamber 129 in which the valve 118 operates. From the chamber 129 the air passes through the diagonally drilled conduit 130, shown in phantom in Figs. 11, 12, 13 and 14, to the position in which this conduit communicates with the horizontal conduit 131, from which the air passes upwardly through conduit 132 into the space below the cup piston 34, as most clearly illustrated in Fig. 12. The air passing through these passages causes the piston to rise until the air is cut off by the rotation of the hand wheel 113, or alternatively, until the jack piston reaches the top of its stroke, at which point the upper surface of the outer portion of the circular plate 33 contacts the under surface of the guide ring 22.

When the lowering of the jack is desired, a valve 135 normally in contact with a seat 136 is opened by means of the relief hand wheel 137 permitting the air to escape from the under side of the piston by reverse flow through the same passages through which the air was admitted, thence through the diagonally drilled conduit 138, past the valve seat and valve 136 and 135, and to atmosphere through the drilled conduit 139. By moving the valve 135 only slightly from the seat 136 the lowering of the jack may be made very gradual, whereas by moving the valve 135 a substantial distance from its seat 136 the jack will be caused to lower quickly.

When it is desired that the jack shall operate to joggle a vehicle, the hand wheel 125 is rotated in a counter-clockwise direction until the sealing ring 120 presses against its seat 122 closing at this point the communication heretofore described for the passage of compressed air into the compartment 129 in which the valve 118 operates. With the valve 118 in its jiggling position, compressed air is admitted by the rotation of the hand wheel 113 and the consequent movement of the valve 111 from its seat 112. The air thus admitted to the valve chamber 116 now passes through drilled conduit 79, thence through conduits 130, 131 and 132 to the under side of the piston.

When the jack piston is raised to the top of its stroke, the reciprocable sleeve 88 and its associated valve block 77 are moved to their upper position by means hereinbefore described, thus closing the entrance to the drilled conduit 79 and connecting that conduit through the depression 78 in the valve block 77 with conduit 80, through which the air now passes from the cylinder to the space within the bore of plug 142, into which is threaded a screw 143 from which the apex of its thread has been removed or omitted, as shown at 144, Fig. 10.

By adjusting the screw 143 inwardly or out-

wardly, the length of the triangular passageway between the flat portions of the threads of the screw 143 and the apex of the threads in the plug 142 may be changed to change the resistance of the flow of air out of the cylinder. By this means the speed of lowering of the jack cylinder may be regulated, whereas the speed of rise of the jack cylinder will be regulated by the adjustment of the hand wheel 113.

When the piston reaches a predetermined point in its downward movement, the sleeve 88 and valve block 77 are moved downwardly by the means above described for putting the bore 79 again into communication with the chamber 116 as shown in Fig. 10 for enabling the compressed air again to raise the piston. This alternate upward and downward movement of the piston continues normally until the valve 118 is again moved toward the left to the position as shown in Fig. 10.

It will be understood that the diameter of the cylinder and housing 21 will be selected in accordance with the weight of the vehicle to be lifted and the air pressure available. Inasmuch as my jack is intended primarily for use in automobile service stations, the air pressure available will ordinarily be that provided for the inflation of automobile tires, usually held at about 100 pounds per square inch in the service tank.

While I have shown and described particular embodiments of my invention, it will be apparent to those skilled in the art that numerous modifications and variations may be made without departing from the underlying principles of the invention. I therefore desire, by the following claims, to include within the scope of the invention all such modifications and variations by which substantially the results thereof may be obtained by substantially the same or equivalent means.

Having thus described my invention, what I claim as new and desire to secure by Letters Patent of the United States is:

1. In a jack comprising a cylinder with a pneumatically operated piston therein, an air induction passageway leading to said cylinder, a pressure supply valve and a pressure release valve controlling said passageway and both operable at will, together with a manually operable valve having a chamber included in said passageway, a pair of seats with which said valve is alternatively engageable, and an automatic valve actuated by the piston to cause said piston to rise and fall periodically, the engagement of said manually operable valve with one of its seats serving to close passages leading from the valve chamber directly to said cylinder and to open passages leading from said chamber to the automatic valve to cause said periodic movements of the piston, and the engagement of said valve with the other of said seats serving to cut off communication between said valve chamber and the automatic valve and to open the passages leading directly to said cylinder for placing the piston under control of said pressure supply and pressure release valves.

2. In a jack comprising a cylinder with a pneumatically operated piston therein, an air induction passageway leading to said cylinder, a pressure supply valve and a pressure release valve controlling said passageway and both operable at will, together with a manually operable valve having a chamber included in said passageway, a pair of seats with which said manually operable valve is alternatively engageable, and an auto-

matic valve actuated by the piston within a limited portion of its full range of movement in the cylinder to cause said piston to rise and fall periodically within such limited range, the engagement of said manually operable valve with one of said seats serving to close passages leading from the valve chamber directly to said cylinder and to open passages leading from said chamber to the automatic valve to cause said periodic movements of the piston, and the engagement of said valve with the other of said seats serving to cut off communication between the valve chamber and the automatic valve and to open the passages leading directly to said cylinder for placing said piston under control of said pressure supply and pressure release valves.

3. In a jack, the combination of a piston movable vertically in a cylinder, means providing two chambers, means for feeding air under pressure to one of said chambers, means connecting the other of said chambers with said cylinder underneath said piston, two separate connections between said two chambers, manually operable valve means for closing either of said separate connections while leaving the other open, other valve means adapted in one operative position to close one of said connections and to connect said other chamber with an exhaust opening, and automatically operated means for moving said last named valve means alternately into and out of said one operative position.

4. In a jack, the combination of a piston movable vertically in a cylinder, means providing two chambers, means for feeding air under pressure to one of said chambers, means connecting the other of said chambers with said cylinder underneath said piston, two separate connections between said two chambers, manually operable valve means in said other chamber for closing either of said separate connections while leaving the other open, other valve means in said one chamber adapted in one operative position to close one of said separate connections and to connect said other chamber with an exhaust opening, and automatically operated means for moving said last named valve means alternately into and out of said one operative position.

5. In a jack, the combination of a piston movable vertically in a cylinder, means providing two chambers, means for feeding air under pressure to one of said chambers, means connecting the other of said chambers with said cylinder underneath said piston, two separate connections between said two chambers, manually operable valve means for closing either of said connections while leaving the other open, other valve means adapted in one operative position to close one of said separate connections and to connect said other chamber with an exhaust opening, and means actuated by the vertical movements of said piston in opposite directions for moving said last named valve means alternately into and out of said one operative position.

6. In a jack, a pneumatically operated hollow piston, a valve operating rod extending into the hollow portion of the piston, a spring surrounding the rod and abutting at one end against an abutment fixed with respect to the piston, an abutment movable with respect to the piston against which the other end of the spring abuts, a projection carried by the piston upon which said movable abutment rests when the spring is in its condition of greatest expansion, a shoulder on the valve operating rod for engagement with the movable abutment for moving the valve op-

erating rod downwardly when the piston moves downwardly to an intermediate position of its stroke, the said valve operating rod being provided with an enlargement for engagement with the upper side of said movable abutment when the piston rises to near the top of its stroke whereby the valve operating rod is moved upwardly, the shoulder on the valve operating rod serving to move the movable abutment relative to the piston when the piston is lowered beyond the intermediate position at which the shoulder on the piston rod engages the movable abutment.

7. In a jack, a piston for movement under air pressure, a cylinder in which said piston may be moved between upper and lower positions by the manual relief of the air pressure under said piston, an automatic valve operating rod, an abutment movable with the piston for engagement with said valve operating rod to move the rod in one direction when the piston approaches the top of its stroke and to move the rod in the other direction when the piston arrives at an intermediate position in its stroke, the said automatic valve serving to admit the release air pressure from the under side of the said piston whereby the piston will reciprocate automatically between two positions less than the complete stroke of the piston, a spring carried by the piston and acting upon said movable abutment to move the automatic valve operating rod in one of its directions, the lowering of the piston below the intermediate position in which the movable abutment engages the automatic valve operating rod serving to compress the spring.

8. In a jiggle jack, a pneumatically operated piston, a slide valve for alternately admitting and releasing air to and from the face of said piston, a pair of opposed springs pressing in opposite directions upon said slide valve in the line of its movement, a part of said slide valve provided with a pair of depressions, a ball which is spring pressed into one of said depressions when the slide valve is in one extreme position and into the other of said depressions when the slide valve is in its other extreme position, and operating means comprising a third spring moved by the piston upon a stroke in one direction for applying pressure on one of said opposed springs to cause the slide valve to move in one direction and moved upon a stroke in the other direction

10

for applying pressure on the other of said opposed springs to cause the slide valve to move in the opposite direction.

9. In a jiggle jack, a pneumatically operated piston, a slide valve for alternately admitting and releasing air to and from the face of said piston, a pair of opposed springs pressing in opposite directions upon a part of said slide valve in the line of its movement, a part of said slide valve being provided with two vertically spaced pairs of oppositely disposed depressions, a pair of balls which are spring pressed toward one another into said depressions on the opposite sides of said part of said slide valve when the slide valve is in one extreme position and into other of said depressions when the slide valve is in its other extreme position, and an operating member moved by the piston at an intermediate point in its downward stroke for applying pressure on one of said opposed springs to cause the slide valve to move in one direction and moved at about the end of the upward stroke of the piston for applying pressure on the other of said springs to cause the slide valve to move in the opposite direction, the said opposed springs permitting the slide valve to move from one position to the other with a snap movement.
